ADDING MACHINE

Linus J. Ritz, Pittsburgh, Pa., assignor to Wolverine Supply and Manufacturing Company, Pittsburgh, Pa., a corporation of Pennsylvania

Application December 7, 1939, Serial No. 308,010

2 Claims. (Cl. 235—80)

This invention relates to adding machines, and the principal purpose in view is the provision of such a machine which may be cheaply manufactured and sold at a relatively small cost, but which will be convenient and simple to use, durable in construction, and which will assure accurate mathematical results.

Another object is the provision of an adding machine which may be embodied in small compass and which may be sold as a useful article for use in the entertaining instruction of children.

In the accompanying drawings, wherein is illustrated a practical embodiment of the present invention,

Fig. 1 is a plan view of the adding machine;

Fig. 2 is an enlarged longitudinal section of the machine taken along the line 2—2 in Fig. 1;

Fig. 3 is an incomplete view similar to Fig. 2 but sectioned on a parallel plane;

Fig. 4 is a perspective view of one of the operating slide bars;

Fig. 5 is a sectional view of the same taken along the line 5—5 in Fig. 4.

Fig. 6 is an inverted plan view of the machine on enlarged scale and with the bottom removed to show parts.

Fig. 7 is an enlarged plan view of the machine with the cover removed to show parts.

Fig. 8 is an enlarged cross sectional view of one of the sliding bars and its mounting.

Referring in detail to the drawings, 10 represents a box, preferably rectangular and formed of sheet metal or other similar material, and provided with a bottom 11, vertical walls 12 and forwardly and downwardly inclined floor or top wall 13.

Spanning the front portion of the interior of the box 10 are two parallel shafts 14 and 15 having their ends received in the side walls of the box.

Both of these shafts are below the plane of the floor 13 of the box and the front shaft 15 is positioned at a lower level than the rear shaft 14.

Rotatably mounted on the rear shaft 14 and in spaced relation are a plurality of indicator wheels generally indicated by the numeral 16 and distinguished as 16a, 16b, 16c and 16d. The wheels are preferably cup-shaped with the outer surfaces of their perimetral flanges provided with a consecutive series of numerals from "0" to "9" inclusive, arranged circumferentially of the wheels.

Any desired number of said disks may be pro-

vided to give the desired working capacity of the machine. In the machine illustrated in the drawings four of the indicator disks are provided, and the machine is arranged to add up to 9999.

5 Each of the wheels 16 is provided with a tubular hub, indicated at 17a, 17b, 17c and 17d, respectively, by means of which the wheel is rotatively mounted on the shaft 14. One end of each hub, the right end looking from the front of the machine is provided with a relatively small star gear 18 having ten teeth and the other end of the hub is provided with a gear 19 of larger diameter than the gear 18, but of less diameter than the disk 16, and also provided with ten teeth.

10 15 Rotatably mounted on the front shaft 15 are a series of spaced apart hubs 20a, 20b, and 20c which are in staggered relation to the hubs 17a, 17b, 17c and 17d on the shaft 14. On one end of each hub 20 is rigidly mounted the star gear 21 having ten teeth and at the other end of the hub a single-toothed gear 22.

15 The gears 21 of the hubs 20a, 20b and 20c are in continuous mesh with the gears 19 of the hubs 17a, 17b and 17c, respectively, while the single-toothed gears 22 of the hubs 20a, 20b and 20c are arranged to engage once in every complete revolution the gears 18 of the hubs 17b, 17c and 17d, respectively, and thus with each complete revolution of the indicator wheel 16a, the indicator wheel 16b is rotated a tenth of a revolution; when the indicator wheel 16b completes a full revolution, the indicator wheel 16c is advanced a tenth of a revolution, and when the indicator wheel 16c completes a full revolution the indicator wheel 16d is turned a tenth of a revolution.

20 25 The gears 21 and 22 are provided at either side with the shrouds 23 between which the teeth of the gears 18 and 19 extend, and thus the gears on the shafts 14 and 15 are maintained in proper alignment with each other.

25 30 The peripheral portions of the wheels 16 and the gears 19 extend up through a transverse opening 24 in the floor 13.

35 40 45 50 55 25a, 25b, 25c and 25d indicate a series of sliding bars equal in number to the indicator wheels 16, and moving on the surface of the floor 13 and each in alignment with but above one of the gears 19 respectively. The bars are resiliently retracted upwardly or rearwardly as by the helical springs 26 whose rear ends are attached to the underside of the floor 13 adjacent the rear end of the same, and whose forward ends are attached to the fingers 27 extending forwardly from the front ends of the bars, the floor being cut away for clearance

for the front portions of the springs as shown at 28.

The cross sectional shape of the bars 25 is that of an inverted channel with the edge flanges provided with an intermediate longitudinal shoulder 29.

30 indicates a series of equally spaced holes cut in the shoulder 29 and flange at one side of each bar 25 and having their rear end walls bent outwardly to form a rack arranged to engage the teeth of the corresponding gear 19 so that as the bar is slid downwardly and forwardly on the floor 13, against the influence of the helical spring, the gear and the corresponding indicator wheel will be rotated to an extent corresponding to the length of the movement of the bar. When the bar is released and is spring returned, the rack travels rearwardly without rotating the gear and wheel in a reverse direction. The bars are provided with finger holes 31 in their top wall arranged longitudinally of the bar and so positioned and spaced apart that when a finger or a pencil is engaged in one of the holes and the bar moved downwardly to the limit of its travel, the gear and wheel will be rotated to the corresponding degree.

The indicator wheels 16 are arranged for revolution in a counterclockwise direction in Fig. 3 and to prevent accidental reverse rotation a spring metal plate 32 is secured to the underside of the floor 13 in the rear of the opening 24 in the floor, and 33 indicates spring fingers which extend forwardly and engage the gears 18 to prevent reverse rotation of the latter. Also there are provided the spring metal strips 34 which have angular arcuate extremities which form shoes 35 to engage the inner surfaces of the perimetral flanges of the indicator wheels 16 to act as brakes to prevent the wheels from excess movement or spinning when they are rotated by the movement of one of the slide bars.

The material of the floor 13 at the front of the opening 24 is bent downwardly, forming a flange 36 having at its free edge the broad fingers 37, which extend between the exterior shrouds 23 of adjacent hubs, thus preventing movement of the hubs 17 and 20 in the shafts 14 and 15, and thus preventing misalignment of parts. The floor 13 forward of the opening 24 is also slotted longitudinally as at 44 to provide clearance for the springs 26 as the slides 25 approach the limit of their forward travel.

38 indicates the pressed metal cover which is provided with a perimetral edge flange 39, whose lower edge is beaded, to engage the floor 13 and hold the cover in upwardly spaced relation to the floor.

The cover is provided with a transversely disposed series of holes 40 which register with the tops of the wheels 16 to expose the numerals at the tops of said wheels so that the total indicated can be read.

The cover is also provided with longitudinally elongated openings 41 exposing the tops of the bars 25 when the latter are in their upwardly retracted position, and along one side of each of said openings is displayed a series of numbers from "1" to "9" inclusive progressing rearwardly of the machine, and each of said bars is provided with a corresponding number of the finger holes 31 which when the bars are retracted register with the corresponding numerals on the cover. The limit of downward or forward movement of

the bars is provided by the lower ends of the openings 41, as the finger or pencil will engage such end to halt the forward movement of the bar.

5 The arrangement is such that when the finger or pencil is engaged with the first hole at the lower end of the bar 25 and the bar is moved forwardly to the limit of its travel, the corresponding indicator wheel 16 is rotated one-tenth of its full revolution, and likewise in whatever opening in the bar the finger is placed and the bar moved downwardly to the lower extremity of its path, the corresponding wheel 16 is rotated to the fraction of its complete revolution indicated by the numeral on the cover registering with that particular opening in the bar when the bar is retracted to its uppermost position.

Again as the total of digits registered on the wheel 16a reaches ten, that wheel indicates "0," 20 while the second wheel 16b is rotated a tenth of a revolution and indicates "1." When the total registered on the wheel 16b reaches ten, that wheel registers "0" and the wheel 16c is rotated a tenth of a revolution to indicate "1." Likewise when the total indicated on wheel 16c reaches ten, the wheel 16d is rotated a tenth of a revolution and indicates "1." Thus the increasing total of a sequence of additions is indicated on the wheels up to the limit of nine thousand nine hundred and ninety-nine. By the provision of additional wheels the maximum total which may be registered may be increased as desired.

35 The bars are held against excess upward movement in response to the influence of their helical springs by means of a flange 42 partially cut out and struck up from the floor 13.

The bars are held against lateral movement from their proper paths by means of the downwardly flanged edges 43 of the openings 41 in the cover, which edges are slidably engaged from below by the shoulders 29 of the bars.

40 In cases where the adding machine is to be used to add sums of money including fractions of a dollar, the first two wheels at the right of the machine may be used for adding and indicating the cents, and the remaining wheel to the left for indicating the dollars.

50 It is apparent from the foregoing that the adding machine herein illustrated and described is of simple yet rugged and durable construction and is accurate in the mathematical results obtained thereon. Also it may be manufactured for sale at a relatively small price.

I claim:

1. An adding machine slide comprising a U-shaped channel member, the side flanges of the channel member being offset to produce shoulders longitudinally thereof, spaced digit openings in the web portion of the channel member for receiving means to move the slide, and a gear rack formed in the offset shoulder along one side of the channel member.

2. An adding machine slide comprising a U-shaped channel member, the side flanges of the channel member being offset to produce shoulders longitudinally thereof, spaced digit openings in the web portion of the channel member for receiving means to move the slide, and a gear rack formed longitudinally of the channel member.

LINUS J. RITZ.
